SELF-LEVELING DISPENSER

Henry H. Rothschild, Teaneck, N.J., assignor to Caddy Corporation of America, Secaucus, N.J.

Filed Mar. 13, 1969, Ser. No. 16,231

Term of patent 14 years

Int. Cl. D6—99; D12—02

U.S. Cl. D52—2

FIG.1

FIG.2

FIG.3

FIG. 1 is a perspective view of the self-leveling dispenser showing my new design.

FIG. 2 is a top plan view of the dispenser.

FIG. 3 is a side elevation thereof, with portions fragmentarily shown for ease of illustration.

The broken lines are shown for illustrative purposes only and form no part of the claimed design.

I claim:

The ornamental design for a self-leveling dispenser, as shown and described.
